(57) **CLAIM**

We claim the ornamental design for a paint applicator handle, as shown and described.

DESCRIPTION

This application is related to U.S. patent application Ser. No. 29/153,826 entitled Paint Applicator Handle filed on the same date by Matthew G. Goulet originally including 25 figures, the full disclosure of which is hereby incorporated by reference, and U.S. patent application Ser. No. 29/153,851 entitled Paint Applicator Handle filed on the same date herewith by Matthew G. Goulet including 32 figures, the full disclosure of which is hereby incorporated by reference.

FIG. 1 is a perspective view of a paint applicator handle of the present invention;

FIG. 2 is a top plan view thereof, the bottom plan view being a mirror image of the top plan view;

FIG. 3 is a rear elevational view thereof;

FIG. 4 is a front elevational view thereof;

FIG. 5 is a left end elevational view thereof;

FIG. 6 is a perspective view of a first alternative embodiment of the paint applicator handle of FIG. 1;

FIG. 7 is a top plan view thereof, the bottom plan view being a mirror image of the top plan view;

FIG. 8 is a rear elevational view thereof;

FIG. 9 is a front elevational view thereof;

FIG. 10 is a left end elevational view thereof;

FIG. 11 is a perspective view of a second alternative embodiment of the paint applicator handle of FIG. 1;

FIG. 12 is a top plan view thereof, the bottom plan view being a mirror image of the top plan view;

FIG. 13 is a rear elevational view thereof;

FIG. 14 is a front elevational view thereof; and,

FIG. 15 is a left end elevational view thereof.

The ornamental design which is claimed is shown in solid lines in the drawings. The broken lines in the drawings are for illustrative purposes only and form no part of the claimed design.

1 Claim, 6 Drawing Sheets
